UNITED STATES PATENT OFFICE.

WILHELM SCHMIDT, OF WILHELMSHÖHE, NEAR CASSEL, GERMANY.

SMOKE-TUBE SUPERHEATER.

Specification of Letters Patent. Patented Aug. 11, 1914.

Application filed May 15, 1909. Serial No. 496,219.

To all whom it may concern:

Be it known that I, WILHELM SCHMIDT, a resident of Wilhelmshöhe, near Cassel, Germany, have invented certain new and useful Improvements in Smoke-Tube Superheaters, of which the following is a specification.

My invention relates to superheaters to be used in connection with steam boilers and has for its object to provide a construction in which sufficient superheating surface is obtained while avoiding certain difficulties which have been experienced in the manufacture and setting up of such apparatus.

There has been a general tendency to increase the number of smoke tubes fitted with superheating tubes. Difficulties have been found as regards the construction of the individual elements and their assembling, especially as regards securing them to the steam collecting chamber. It is always desirable that the several superheater elements should be capable of being detached or cut out individually and accordingly it has been proposed to employ a separate superheating unit for each row of smoke tubes, said unit being built up of not more than one individual loop to a single smoke tube, such construction lends itself most readily to the extraction or repair of individual superheater elements without disturbing other elements. If this arrangement, however, is applied to a large number of smoke tubes situated in the same plane, the cross section of the steam current becomes too small and the path of the steam too long with the result that either the superheating is carried too far, or that the superheating tubes will become red-hot and; at the same time the heat is not utilized efficiently. To avoid these defects I have adopted constructions of the character illustrated in the accompanying drawings, in which—

Figure 1 is a sectional elevation through part of a superheater embodying my invention; Fig. 2 is a vertical section on line 2—2 of Fig. 1; Fig. 3 is a horizontal section showing still another form of my invention; and Fig. 4 is a vertical section on line 6—6 of Fig. 3.

In the form of my invention illustrated by Figs. 1 and 2 a plurality of smoke tubes s are located in the same plane. The superheater elements are contained in these smoke tubes, but instead of comprising a single

unit of many loops, said loops are arranged in two groups, each of said groups having its own connected ends for the entry of saturated steam and exit of superheated steam. These two groups are connected to the headers in parallel so as to receive and superheat different volumes of steam.

a indicates the chamber which receives the steam from the boiler and from which the steam passes to the two sets of superheater tubes c and d through separate supply connections c' and d' . The superheated steam leaves the two sets of the superheater tubes c and d through connections c^2 and d^2 respectively which lead to the collecting chamber b . It will be obvious that with this construction the path of the steam from the chamber a to the chamber b is shorter than if the steam were made to travel through all of the tubes c and d before reaching the chamber b . With my invention I avoid sending the steam through a path which is too long for the securing of efficient and economic results.

The construction shown in Figs. 3 and 4 is similar to that represented in Figs. 1 and 2, except that the smoke tubes s^2 lie in the same horizontal plane instead of being superposed, and four sets of superheating tubes (c^a — c^b , d^a — d^b) are connected with the steam supply chamber a^2 and with the collecting chamber b^2 respectively.

Dividing the superheater into units as thus described offers advantages of the same order as would be obtained by using a single loop in a single smoke tube as a complete superheater unit as regards the facility of assembling the structure and of removing parts of sections thereof without disturbing the others. Furthermore, as has been fully explained, the utilization of the heat is much more efficient owing to the shorter path through which each particle of steam has to travel.

The chambers or headers a' , b' , a^2 , b^2 may be common to all the superheater units, or divided into sections as required, but I prefer that the headers for the saturated steam coming from the boiler and for the superheated steam respectively should be separate castings.

I claim as my invention:

1. In a superheater, a plurality of rows of smoke tubes, and a plurality of superheater units in each row, each unit comprising a plurality of loops, all of said loops of the

- several units of each row being arranged in the same plane but the pairs of ends from said several units being arranged in different planes, as and for the purpose described.
- 5 2. In a superheater, a plurality of rows of smoke tubes, and a plurality of superheater units in each row each unit comprising a plurality of loops, all of said loops of the several units of each row being arranged in the same plane while the pairs of ends from said several units are arranged in planes parallel to one another, as and for the purpose described.
- 10 3. In combination, a plurality of rows of smoke tubes, a plurality of superheater units in each row each unit comprising loops arranged in series and all the loops of each row being arranged in the same plane, headers for the saturated and superheated steam respectively, and pairs of ends between the headers and the superheater units said pairs
- of ends being arranged in parallel planes, as and for the purpose described.
4. In combination, a plurality of smoke tubes, arranged in rows, a plurality of superheater units in each row each unit comprising loops and the loops being arranged in series in substantially every one of the tubes of a given row all of said loops of each row being arranged in the same plane, headers for the saturated and superheated steam respectively, and pairs of ends between the headers and the superheater units said pairs of ends being arranged in parallel planes, as and for the purpose described.
- 15 In testimony whereof I have hereunto set my hand in the presence of two subscribing witnesses.
- 20 WILHELM SCHMIDT.
